UNITED STATES PATENT OFFICE.

HERBERT ELLIOTT, OF TORONTO, ONTARIO, CANADA.

DESIGN FOR A TOY.

47,183.

Specification for Design.

Patented Apr. 6, 1915.

Application filed January 12, 1915. Serial No. 1,893. Term of patent 3½ years.

To all whom it may concern:

Be it known that I, HERBERT ELLIOTT, a subject of the King of Great Britain, and a resident of the city of Toronto, in the county of York, in the Province of Ontario, in the Dominion of Canada, have invented a new, original, and ornamental Design for Toys, of which the following is a specification, reference being had to the accompanying drawing, forming part thereof.

The figure is a perspective view of a toy, showing my new design.

The design consists of the grotesque caricature of a dog having a distinguishing up-standing ear.

I claim:

The ornamental design for a toy, as shown and described.

Signed at Toronto, in the county of York, in the Province of Ontario, in the Dominion of Canada, this 8th day of January, 1915.

HERBERT ELLIOTT.
